John L. Shaw

United States Patent Office.

JOHN L. SHAW, OF GRAND RAPIDS, MICHIGAN.

Letters Patent No. 99,247, dated January 25, 1870.

IMPROVEMENT IN SHOVEL-HANDLE.

The Schedule referred to in these Letters Patent and making part of the same.

To all whom it may concern:

Be it known that I, JOHN L. SHAW, of the city of Grand Rapids, county of Kent, and State of Michigan, have invented a certain new and useful tool or implement, which I call a Combined Shovel-Handle and Tamping-Bar; and do hereby declare that the following is a full, clear, and exact description of my invention, reference being had to the accompanying drawings, and the letters of reference marked thereon, and the same are made a part of these specifications.

Figure 1 represents a general view of my invention, in perspective, when constructed, ready for use.

Figure 2 represents a metallic cylinder, provided with semi-cylindrical projections, and is designed to be used as a hand-piece of a shovel-handle or as the lower end of a tamping-bar, whenever the shovel-handle, to which it is attached, is used for this latter purpose.

To enable others who are skilled in the branch of mechanics to which the manufacture of my invention belongs, to make the same, I will proceed to describe its construction.

It consists of an ordinary wooden shovel-handle, with its upper end scalloped or cut out so as to leave a convenient hold for the hand while using the shovel, but instead of making the hand-piece of the same piece of wood as the rest of the handle, this part is entirely cut away, leaving only the side-pieces or forks represented by F F in fig. 1.

The hand-piece, as shown by C, in fig. 2, is composed of a cylinder of iron or other suitable metal, provided with semi-cylindrical projections, one on each end, as shown by letters P P, in fig. 2.

The cylinder is filled with wood or other suitable substance, in order that the bolt or rivet which attaches it to the handle of the shovel, may hold it firmly in its place.

The forks or sides of the handle shown in fig. 1, by the letter, F F, are rounded at their upper ends, so as to fit closely into the semi-cylindrical projections above

described, while the shorter ends of the cylindrical hand-piece fit closely between the sides of the handle F F, as shown in fig. 1.

A strong bolt or rivet is passed through the forks or sides of the handle, and through the cylindrical hand-piece of the handle, and firmly headed down upon each end.

This cylindrical hand-piece is equally well adapted to shovel-handles sawed or split open at the upper end and bent into substantially the same shape as the parts represented in fig. 1, by the letters F F, as above described.

Instead of making the hand-piece C cylindrical in form, as above described, it may be made of one solid piece of metal, with semi-cylindrical projections, similar to those above described, and attached by means of a bolt or rivet to the handle of the shovel, or by any other suitable attachment; but I deem the cylindrical hand-piece the cheapest and lightest, and equally strong and durable.

The advantage of my invention consists, principally, in its great strength and durability and in its adaptability to the work of packing earth or dirt in close proximity to solid substances, as is often required in the construction of railroad-beds, post-setting, &c., thus forming a combined shovel-handle and tamping-bar, enabling the operator in many cases to perform his work with one tool or implement instead of two.

What I claim to have invented, and desire to secure by Letters Patent of the United States, is—

A combined shovel-handle and tamping-bar, constructed by attaching to an ordinary wooden shovel-handle the metallic hand-piece or cylinder C, when constructed and operating substantially as above set forth.

In witness that I claim the above, I have hereunto set my hand, this 8th day of July, A. D. 1869.

JOHN L. SHAW.
